UNITED STATES PATENT OFFICE

WILLIAM PALMER, OF BUFFALO, NEW YORK, ASSIGNOR OF ONE-HALF TO ERNEST W. ASTELS, OF BUFFALO, NEW YORK

COMBINED IRONING BOARD AND TABLE

Application filed May 18, 1928. Serial No. 278,865.

The principal object of my invention has been to provide a structure in which the ironing board when not in use shall complete and form a part of the top of a table.

Another object has been to provide a device in which a collapsible supporting member for the ironing board shall be folded out of sight and occupy a position under the table top when the ironing board is not in use, but which may be quickly and easily brought to its operative position when the ironing board is removed from the table top and ready to use.

Another object has been to provide a device of this nature which shall be inexpensive to manufacture and shall be convenient and handy to use.

The above objects and advantages have been accomplished by the device shown in the accompanying drawings, of which:

Fig. 1 is a side, sectional elevation of my device in its operative position, and is taken on line 1—1 of Fig. 2.

Fig. 2 is a fragmentary, transverse, sectional elevation of the device in the same position and is taken on line 2—2 of Fig. 1.

Fig. 3 is a transverse, sectional elevation showing the ironing board in its closed position and serving to continue the table top and is taken on line 3—3 of Fig. 4.

Fig. 4 is a plan view of the invention with the board in the position shown in Fig. 3.

My invention comprises a table top 10 which is provided with an opening 11, substantially of the size and shape as the size and shape of the ironing board 12, which is disposed in the opening when the device is in its inoperative position. The table is provided with the usual side boards 13 and end boards 14, which support the top of the table and the table legs 15 in a well known manner.

Secured to the inside of each of the side boards 13 is a cleat 20 which is interspaced from the top 11 of the table and thus provides a guideway 22 for the slide 21 which is thus movable beneath the opening 11 and in a plane substantially parallel to the top. The slide carries the supporting member 23. An abutment or stop 16 is carried on the lower side of the slide 21, which serves to limit the

movement of the supporting member 23 when in its closed position as shown in Fig. 3. The supporting member is provided with a top wall 24 and with a bottom wall 25. End walls 26 and 27 are also provided as well as side walls 31. This arrangement provides a compartment 28 into which the iron may be stored when not in use, the top wall being provided with an opening 32 by which the compartment 28 is accessible. The top wall 24 is pivotally connected to the slide 21 preferably by hinges 33, so that when the ironing board 12 is removed from the opening 11 in the table top, the supporting member may be moved from its lower inactive position, as shown in Fig. 3 through the opening 11 to its operative position as shown in Fig. 1. When in this position, the top surface of the top wall 24 will contact with and be supported by the top surface of the slide 21.

The wall 27, as shown in Fig. 1, acts as a support for the board 12, and the opposite wall 26 which extends some distance above the wall 27 is provided with a plurality of hooks 29 which are arranged to engage a cleat 30 on the end of the board, so as to support this end of the board against vertical movement, and also to so engage it that the end of the board shall be prevented from slipping out from underneath the hooks. The cleat 30 is preferably made longer than the width of the end of the board where it is provided, so that it will engage the under surface of the table top 10 on each side of the opening 11 and thereby hold this end of the board down flush with the table top.

It is obvious from the foregoing that when one has finished using the board, it is only necessary to move the outer end of the board upwardly so as to disengage the cleat 30 from the hooks 27 whereupon slide 21 with the supporting member 23 may be moved to the left, as shown in Figs. 1 and 3, and the supporting member folded down into the table top to the position shown in Fig. 3. The board is then turned over and put in place in the opening 11 as shown in Figs. 3 and 4.

Obviously, some modifications of the details herein shown and described may be made without departing from the spirit of my in-

vention or the scope of the appended claims, and I do not, therefore, wish to be limited to the exact embodiment herein shown and described, the form shown being merely a preferred embodiment thereof.

5 Having thus described my invention, what I claim is:

1. A device of the character described comprising a table having a top formed with an opening therein, a removable ironing board arranged within the opening, a slidable member mounted beneath the opening and movable in a plane substantially parallel to the top, and foldable supporting means pivotally secured to the slidable member, comprising two interspaced supports for engaging one end of the ironing board and holding it in position for use, one of the supports engaging the ironing board on its under side and the other support engaging the board on its upper side.

2. A device of the character described comprising a table having a top formed with an opening therein, a removable ironing board arranged within the opening, a slidable member mounted beneath the opening and movable in a plane substantially parallel to the top, foldable supporting means pivotally secured to the slidable member comprising a shorter support and a longer support, hooks carried by the longer support, the shorter support engaging the under side of the board, and a cleat secured to the opposite side of the board and engageable with the hooks of the longer support.

3. In a device of the character described, the combination with a table, of a removable ironing board forming a part of the table top and fitting within an opening formed in such top, a slidable member mounted beneath the opening and movable in a plane substantially parallel to the top, and foldable supporting means pivotally secured to the slidable member for engaging and holding the ironing board in position for use.

4. In a device of the character described, the combination with a table, of a removable ironing board forming a part of the table top and fitting within an opening formed in such top, a slidable member mounted beneath the opening and movable in a plane substantially parallel to the top, and foldable supporting means pivotally secured to the slidable member, comprising two interspaced supports for engaging one end of the ironing board and holding it in position for use.

5. In a device of the character described, the combination with a table, of a removable ironing board forming a part of the table top and fitting within an opening formed in such top, a slidable member mounted beneath the opening and movable in a plane substantially parallel to the top, a stop carried by the slidable member, and foldable supporting means for engaging and holding the ironing

board in position for use, such means being pivotally secured to the slidable member and engageable with the stop when in its inoperative position.

In testimony whereof, I have hereunto signed my name.

WILLIAM PALMER.
